UNITED STATES PATENT OFFICE.

NELLA E. BERRY, OF BUFFALO, NEW YORK.

DESIGN FOR A NAIL-BUFFER.

55,406.

Specification for Design.

Patented June 8, 1920.

Application filed March 6, 1920. Serial No. 363,829. Term of patent 14 years.

To all whom it may concern:

Be it known that I, NELLA E. BERRY, a citizen of the United States, residing at Buffalo, in the county of Erie and State of New York, have invented a new, original, and ornamental Design for a Nail-Buffer, of which the following is a specification.

The accompanying drawing is a perspective view of a nail buffer embodying the design.

I claim:

The ornamental design for a nail buffer, as shown.

NELLA E. BERRY.
